COMBINATION LOCK

Albert M. Finek, Bellevue, Ky.

Application December 6, 1946, Serial No. 714,512

8 Claims. (Cl. 70—133)

1

This invention relates to combination locks, and more particularly to a lock of the permutation type which may be operated by sight, sound or feeling.

A main object of the invention is to provide a novel and improved combination lock designed especially for the doors of dwellings, the structural arrangement being such that the lock can be opened from the outside of the dwelling only by a person familiar with the combination but which may be readily opened by any person from the inside of the dwelling.

A further object of the invention is to provide an improved combination lock which may be operated by setting the combination visually, by counting sound impulses, or by counting vibrations, whereby the combination may be set regardless of the presence of daylight or other illumination.

A still further object of the invention is to provide an improved combination lock wherein an attempt to tamper with the lock by an unauthorized person will cause no damage to the mechanism thereof.

A still further object of the invention is to provide an improved combination lock wherein the combination may be readily altered whenever it is desired to change the numerical settings required to open the lock.

Further objects and advantages of the invention will become apparent from the following description and claims, and from the accompanying drawings, wherein:

Figure 1 is a vertical cross-sectional view of a combination lock constructed in accordance with the present invention.

Figure 2 is a cross-sectional view taken on line 2—2 of Figure 1.

Figure 3 is a front elevational view, partly in cross-section, of the lock shown in Figure 1.

Figure 4 is an exploded perspective view of the elements of the combination locking mechanism employed in the lock structure of Figure 1.

Figure 5 is a detail cross-sectional view taken on line 5—5 of Figure 2.

Figure 6 is a detail cross-sectional view taken on line 6—6 of Figure 2.

Figure 7 is a cross-sectional detail view taken on line 7—7 of Figure 1.

Referring to the drawings, 11 designates a door. Secured to the outside of the door is a housing 12 and secured to the inside of the door is another housing 13, the main portion of which is recessed into the door. The door is formed with an opening 14 in which portions of housings 12 and 13

2

face each other. The inner portion of housing 12 which is received in opening 14 is formed with a cylindrical bore 15. Rotatably positioned in bore 15 is an annular stepped member 16 having an outer flange 17 and an intermediate cylindrical bearing surface 18. Rotatably mounted on bearing surface 18 and retained against outward axial movement by flange 17 is an annular clamping ring 19. Secured to clamping ring 19 by bolts 20, 20 is a flanged knob 21. Knob 21 may be rotatively adjusted with respect to stepped member 16 by loosening bolts 20, 20. When said bolts are tightened, knob 21 is clamped to said stepped member by the clamping ring 19.

Secured to the inner portion of the periphery of knob 21 is a ring 22 having a serrated outer periphery. The serrations comprise groups of four minor indentations 23 separated by major indentations 24 of greater depth than the minor indentations 23. Each serration corresponds to a calibration mark of dial markings carried by knob 21, and the angular spacing between successive major indentations 24 corresponds to the spacing between five units on the dial scale.

Below knob 21, housing 12 is provided with a vertical compartment 25 having an outer wall 26. Wall 26 is formed with a vertical slot 27 and a projection 28 at the top of said slot. Vertically slidably in compartment 25 is a vertical bar member 29 carrying a lug 30 at its top end. Passing through slot 27 is a bolt member 31 threadedly secured to bar member 29. Rotatably mounted on bolt member 31 is an eccentric cam 32 to which is secured a knob 33. Positioned in the bottom of compartment 25 is a coiled spring 34 which bears upwardly on a follower plate 35 underlying bar member 29. Spring 34 biases bar member 29 upwardly and biases eccentric cam 32 into contact with projection 28.

The periphery of knob 21 is formed with a zero recess 36 adapted to receive lug 30 to indicate a predetermined zero setting of knob 21 with respect to housing 12.

Vertically slidable in compartment 25 behind bar member 29 is a dog 37 formed with a tooth 38 at its top end. A coiled spring 39 is positioned between the bottom of dog 37 and follower plate 35 to bias dog 37 upwardly. Tooth 38 engages the serrations in ring 22 and provides a clicking sound with accompanying vibration as the knob 21 is rotated.

Lug 30 may be withdrawn from zero recess 36 by rotating knob 33 one-half turn from the position shown in Figure 1. Normally spring 34 biases said lug against the periphery of knob 21 and

when said knob 21 is rotated, lug 30 snaps into recess 36 upon being brought into registry therewith. As explained above, this establishes a predetermined zero setting of knob 21.

Slidably positioned in stepped annular member 16 is a sleeve member 41 which is keyed to member 16 by a key 40 engaged in a longitudinal keyway formed in the bore of member 16. The forward portion of sleeve member 41 is loosely received in an axial bore 42 formed in knob 21. The rearward portion of sleeve member 41 projects into housing 13. Sleeve member 41 is formed with a rearward bore portion 43 and a forward bore portion 44 which is enlarged with respect to rearward bore portion 43. Slidably positioned in rearward bore portion 43 is a shaft member 45 having a reduced forward portion 46. Encircling said reduced portion is a washer 47 which is slidable in forward bore portion 44 of sleeve member 41 and a coiled spring 48. Spring 48 is pressed against washer 47 by a sleeve 49 slidably mounted on the forward end of portion 46 and held thereon by a washer 50 which slidably fits into an enlarged end bore 51 formed in sleeve 49 and is secured to portion 46 by a machine screw 52. The bore in knob 21 is enlarged at its outer end, as shown at 53 and slidably fitting therein is an annular member 54 which also is slidable on sleeve 49. A headed screw 55 is threaded into the end of bore 51 and retains member 54 in bore 53. A coiled spring 56 encircles sleeve 49, said spring bearing at one end on the end of sleeve member 41 and at the other end on annular member 54, whereby said annular member is biased outwardly against the head of screw 55. There is sufficient clearance between washer 50 and the end of screw 55 to permit sleeve 49 to be moved inwardly against the pressure of spring 48 and the pressure of spring 56 acting on annular member 54 until said annular member engages the shoulder at the inner end of bore 53. Thus, if shaft 45 is locked, the head of screw 55 can be pushed inwardly without causing any damage to the other parts of the lock. If the lock is set to its released condition, such inward pressure on screw 55 will be transmitted to shaft 45 through spring 48 and washer 47 to move shaft 45 inwardly, as will be subsequently described.

Instead of being slidable on sleeve 49, as above described, annular member 54 may be rigidly secured to or be made integral with said sleeve within the spirit of the present invention.

Housing 13 has an inner cap 57 to which is secured a tumbler casing 58 which has a cylindrical portion coaxial with shaft 45. Sleeve member 41 is formed at its end with a flange 59 slidably fitting inside the cylindrical portion of said casing. Flange 59 is formed with a notch 60. Between flange 59 and the adjacent wall surface of cap 57 is a washer 61 which encircles sleeve member 41. A pair of biasing springs 62, 62 seated in recesses in the wall of cap 57 exert rearward spring pressure on washer 61. Washer 61 is formed with a notch 63 similar in shape to notch 60. Projecting from the end of sleeve member 41 is a tumbler pin 64. Rearwardly adjacent flange 59 is a ring 65 formed with a peripheral projection 66 slidably engaged in a longitudinal groove 67 formed in the bottom wall of casing 58. Ring 65 has a gap 68 of similar shape to notch 60 and registerable therewith. Rearwardly adjacent ring 65 is a disc 69 rotatable and slidable on shaft 45 and formed with a peripheral notch 70 of similar shape and registerable with

notch 60. Disc 69 carries a forwardly projecting pin 71 and a rearwardly projecting pin 72. Pin 71 is engageable by tumbler pin 64. Rearwardly adjacent disc 69 is a ring 73 similar to ring 65 and having a bottom projection 74 slidably received in groove 67 and a gap 75 aligned with gap 68. Rearwardly adjacent ring 73 is a disc 76 similar to disc 69 and having a notch 77 and a forwardly projecting tumbler pin 78 which is engageable with pin 72. Disc 76 is urged by the pressure of springs 62, 62 acting through the intervening elements 61, 59, 65, 69 and 73 into frictional contact with the rear wall 79 of casing 58.

Shaft 45 projects through rear wall 79 and is provided with a flange member 80 which is normally rearwardly adjacent said rear wall. Pivotally mounted in housing 13 and casing wall 79 adjacent flange member 80 and on an axis parallel to shaft 45 is a detent member 81. Detent member 81 is flanged at one end, as shown at 82 and is reduced in diameter adjacent flange 82 to define a neck portion 83. The end of flange member 80 is formed with an elongated notch 84 adapted to rotatably receive neck portion 83. Detent member 81 carries a depending dog 85 slightly greater in length than the combined thickness of the tumbler elements 61, 59, 65, 69, 73 and 76 and is longitudinally spaced from flange 82 by an amount slightly greater than the thickness of rear wall 79 of the tumbler casing 58. As shown in Figure 6, the detent member 81 passes rotatably through said rear wall 79 and the dog 85 is adapted to enter the notch elements 63, 69, 68, 70, 75, and 77 when said notch elements are in registry. A spring 86 carried by shaft 45 has an arm portion 87 which engages dog 85 and biases said dog toward notch-engaging position. When the notch elements are not in registry, the dog 85 bears on the peripheries of the respective rotatable tumbler elements 59, 69, and 76.

Thrust washer 61 has a depending lug 88 fitting into a suitable recess in the wall of cap 57 and aligned with groove 67. The notch 63 of said washer is thereby maintained constantly in alignment with the gaps 68 and 75 of the respective non-rotating rings 65 and 73. When the notches 60, 70 and 77 are brought into registry with the stationary notches 63, 68 and 75, the dog 85 snaps into the aligned notches under the pressure exerted thereon by arm 87 of spring 86. The disc 76 is rotated to unlocking position by the coaction of pin 72 with the pin 78 carried by said disc as knob 21 is rotated in one direction to the first number of the combination. Disc 69 is then rotated to unlocking position by the coaction of pin 64 with the pin 71 carried by disc 69 as the knob 21 is rotated in an opposite direction to the second number of the combination. Flange 59 is then rotated to unlocking position by rotating knob 21 in the first direction to the third number of the combination.

The opening in end wall 79 of tumbler casing 58 through which detent member 81 passes is formed so that dog 85 is slidable therethrough only when said dog is seated in the registering notch elements, i. e., when the rotatable tumbler elements have all been moved to unlocking position. At all other times dog 85 is restrained against rearward endwise movement by wall 79. Since flange member 80 is engaged in neck portion 83 of detent member 81, shaft 45 is thereby also restrained against rearward endwise movement unless the rotating tumbler elements have all been moved to unlocking position. When the

unlocking positions of said rotating elements have been established, pressure on the head of screw 55 will be transmitted through spring 48 and washer 47 to said shaft and the shaft will be moved rearwardly.

Shaft 45 has a rear extension 89 which is slidably received in a bore 90 formed in a sleeve member 91. Sleeve member 91 is formed with an enlarged end bore 92 in which is slidably positioned a washer 93 which is secured to the end of shaft extension 89. Threaded into the end of bore 92 is a headed screw 94 and positioned in bore 92 between the inner end of screw 94 and washer 93 is a tensioned coil spring 95. The end of sleeve 91 and screw 94 protrude from a projection 96 formed in the wall of housing 13 on the inside of door 11. Sleeve 91 is slidable in projection 96. The inner portion of sleeve 91 has a pair of depending projections 97 and 98 slidable in a keyway 99 formed in the bore 100 in which sleeve 91 is received. In the normal position of sleeve 91, projection 98 is fully emerged from keyway 99, as shown in Figure 1. The recess between projections 98 and 97 is shown at 101.

Journaled in the walls of housing 13 parallel to shaft 45 is a shaft 102. Secured to shaft 102 is a body member 103 formed with a first gear sector 104 and a second gear sector 105. Gear sector 105 has a substantially larger radius than sector 104. Slidably mounted in housing 13 above gear sector 105 is a latch bolt 106 comprising a housing 107 in which a latch element 108 is slidably positioned. Latch element 108 carries a pin 109 which projects into a slot 110 formed in the adjacent top wall of housing 107. A spring 111 seated inside housing 107 bears outwardly against latch element 108 and biases said latch element outwardly, yet permits the latch element to be pushed inwardly when the door is being closed. Housing 107 is formed at its lower wall with rack teeth 112 which are in mesh with the teeth of gear sector 105. Slidably mounted in housing 13 below gear sector 104 is a plunger member 113 formed with rack teeth 114 meshing with the teeth of gear sector 104. Projecting from plunger member 113 is a pin 115. Engaging pin 115 is an arm 116 of a heavy spring 117 carried on a post 118 in housing 13 and having its other arm 119 held stationary in said housing. As viewed in Figure 2, arm 116 exerts a powerful counter-clockwise force which tends to urge plunger member 113 outwardly and to rotate shaft 102 counter-clockwise because of the meshing of rack teeth 114 with gear sector 104. This, of course, also tends to retract latch bolt 106. Shaft 102 is held in locking position by a dog member 120 pivoted at 121 to housing 13 and having a vertical bar portion 122 whose upper end underlies and abuts depending projection 98 of sleeve member 91 and whose lower end rests on a cam 123 carried by body member 103. When sleeve member 91 is moved either inwardly or outwardly a sufficient distance so that the top end of bar portion 122 is unobstructed, spring 117 is free to rotate shaft 102, inasmuch as the cam 123 is then free to raise the bar portion 122 from the low point on the cam periphery to the high point thereon. This of course retracts latch bolt 106 from its locking position and at the same time moves plunger 113 outwardly a short distance. The latch housing 124 with which the latch bolt 106 cooperates, however, has a yieldable flap 125 which yields as plunger 113 engages it when the door is being opened so that the outward projection of plunger 113 does not interfere with the opening of the door.

Assuming that the door is locked and that it is desired to open the door from the outside, the first step is to rotate knob 33 to the low point on eccentric cam 32 and then to proceed to rotate knob 21 until lug 30 enters recess 36, thus establishing the zero setting. Knob 33 is then turned to the high point on cam 32 where it will be held by projection 28. The combination is then set as above described by rotating knob 21 in the prescribed manner. This may be done either visually or by counting vibrations or clicking sounds as where the lock is operated in the dark. A heavy click represents five units of dial setting, whereas a light click represents one unit. After the combination is set, head screw 55 is pushed inwardly, causing shaft 45 to be moved likewise, since detent member 81 is now released. This moves sleeve member 91 rearwardly and causes projection 98 to move into keyway 99 and out of the path of the top end of bar portion 122. Spring 117 is now free to move plunger member 113 outwardly, since cam 123 is released and shaft 102 is free to turn. The rotation of shaft 102 in a counter-clockwise direction, as viewed in Figure 2, causes latch bolt 106 to be retracted.

The same result may be accomplished from the inside of the door 11 by merely pressing headed bolt 94. This moves sleeve member 91 so that recess 101 overlies the top end of bar member 122, allowing free upward movement of said bar member.

In closing the door, the plunger member 113 engages the aforementioned flap member 125 in the latch housing and is forced back, said flap member being yieldable only in the opening direction of movement of the door. This rotates shaft 102 clockwise, as viewed in Figure 2, spring 111 of the latch bolt 106 being meanwhile compressed as latch element 108 is forced inwardly. The clockwise rotation of shaft 102 moves cam 123 to a position wherein the bottom end of bar member 122 may drop to the low point of the cam. The top end of bar member 122 is tapered so that the force of return spring 56 acting on the tapered top end of said bar member aids in returning the bar member to seated position on said cam low point. When the bar member 122 is in its lowered position, sleeve member 91 moves forward and projection 98 overlies the top end of said bar member, restoring the locked condition of the bolt retracting mechanism. Latch element 108 is projected into its recess in the latch housing 124 by spring 111 and the door is now locked.

While a specific embodiment of a combination lock structure for doors has been disclosed in the foregoing description, it will be understood that various modifications within the spirit of the invention may occur to those skilled in the art. Therefore, it is intended that no limitations be placed on the invention other than as defined by the scope of the appended claims.

What is claimed is:

1. In a lock, a sliding bolt, means biasing said bolt to a projecting position, retracting means for said bolt, a rotatable member carried by said retracting means, a swingable dog adapted to interlock with said rotatable member, said swingable dog and said rotatable member being formed at their interlocking portions so that the biasing means is effective to cause the rotatable member to move out of interlocking engagement with the dog unless the dog is restrained, a movable member, a lug element carried by said movable member, and means biasing said movable member to a

position wherein said lug element is in restraining relation to said dog.

2. In a lock, a sliding bolt, means biasing said bolt to a projecting position, retracting means for said bolt, a rotatable cam carried by said retracting means, a swingable dog adapted to interlock with said cam, said dog and said cam being formed at their interlocking portions so that the biasing means is effective to cause the cam to move out of interlocking engagement with the dog unless the dog is restrained, a movable member, a lug carried by said movable member, means biasing said movable member to a position wherein said lug is in restraining relation to said dog, and a permutation lock device for locking said movable member.

3. In a lock, a sliding bolt, means biasing said bolt to a projecting position, retracting means for said bolt, a rotatable cam carried by said retracting means, a swingable dog adapted to interlock with said cam, said dog and said cam being formed at their interlocking portions so that the biasing means is effective to cause the cam to move out of interlocking engagement with the dog unless the dog is restrained, a movable member movable in two directions, a lug carried by said movable member, means biasing said movable member to a position wherein said lug is in restraining relation to said dog, and a permutation lock device formed and arranged to lock said movable member against movement in one of said two directions.

4. In a lock, a sliding bolt, means biasing said bolt to a projecting position, retracting means for said bolt, a rotatable cam carried by said retracting means, a swingable dog adapted to interlock with said cam, said dog and said cam being formed at their interlocking portions so that the biasing means is effective to cause the cam to move out of interlocking engagement with the dog unless the dog is restrained, a movable member movable in two directions, a lug carried by said movable member, means biasing said movable member to a position wherein said lug is in restraining relation to said dog, a permutation lock device formed and arranged to lock said movable member against movement in one of said two directions, and audible signal means formed and arranged to produce periodic sounds responsive to operation of said permutation lock device.

5. In a lock, a sliding bolt, means biasing said bolt to a projecting position, retracting means for said bolt, a rotatable cam carried by said retracting means, a swingable dog adapted to interlock with said cam, said dog and said cam being formed at their interlocking portions so that the biasing means is effective to cause the cam to move out of interlocking engagement with the dog unless the dog is restrained, a movable member movable endwise in two directions, a lug carried by said movable member, means biasing said movable member to a position wherein said lug is in restraining relation to said dog, a permutation lock device formed and arranged to lock said movable member against endwise movement in one of said two directions, and a yieldable push button device carried at each end of said movable member.

6. In a lock, a sliding bolt, means biasing said

bolt to a projecting position, retracting means for said bolt, a rotatable cam carried by said retracting means, a swingable dog adapted to interlock with said cam, said dog and cam being formed at their interlocking portions so that the biasing means is effective to cause the cam to move out of interlocking engagement with the dog unless the dog is restrained, a movable member, guide means for guiding said movable member for endwise movement in either direction, a lug carried by said movable member, means biasing said movable member to a position wherein said lug is in restraining relation to said dog, a permutation lock device formed and arranged to lock said movable member against endwise movement when pushed from one end thereof, a yieldable push button device carried at said one end, and stop means limiting inward movement of said push button device.

7. In a lock, a sliding bolt, means biasing said bolt to a projecting position, retracting means for said bolt, a rotatable cam carried by said retracting means, independent means for rotating said cam against the pressure of said biasing means, a swingable dog adapted to interlock with said cam, said dog and cam being formed at their interlocking portions so that the biasing means is effective to cause the cam to move out of interlocking engagement with the dog unless the dog is restrained, movable means restraining said dog, a permutation lock device formed and arranged to lock said movable means, a knob associated with said permutation lock device, and a vibrator actuated responsive to the rotation of said knob.

8. In a lock, a sliding bolt, means biasing said bolt to a projecting position, retracting means for said bolt, a rotatable cam carried by said retracting means, independent means for rotating said cam against the pressure of said biasing means, a swingable dog adapted to interlock with said cam, said dog and cam being formed at their interlocking portions so that the biasing means is effective to cause the cam to move out of interlocking engagement with the dog unless the dog is restrained, movable means restraining said dog, a permutation lock device formed and arranged to lock said movable means, a knob associated with said permutation lock device, said knob being formed with a recess in its periphery, a yieldable projection member engageable in said recess to establish a predetermined initial setting of said knob, and means for at times retracting said projection member out of engagement with said recess.
